UNITED STATES PATENT OFFICE.

CHARLES LUKENS HUSTON, OF COATESVILLE, ASSIGNOR TO JOHN D. NEWBOLD, OF NORRISTOWN, PENNSYLVANIA.

DEVICE FOR CLAMPING PLATES OR SHEETS OF METAL.

SPECIFICATION forming part of Letters Patent No. 413,945, dated October 29, 1889.

Application filed April 27, 1889. Serial No. 308,799. (No model.)

To all whom it may concern:

Be it known that I, CHARLES LUKENS HUSTON, a citizen of the United States, residing at Coatesville, in the county of Chester and State of Pennsylvania, have invented certain new and useful Improvements in Devices for Clamping Plates or Sheets of Metal; and I do hereby declare the following to be a full, clear, and exact description of the invention, such

as will enable others skilled in the art to which it appertains to make and use the same.

My invention has relation, generally, to devices for clamping or holding sheets or plates of metal while being trimmed or sheared into a circular or other curved configuration of a form wherein one of two clamping heads or disks has a movement to and from the other by means of an actuating pressure-screw, and both disks, together with the plate of metal clamped between them, have a rotary movement on their axis to feed the outer rim or edge part of the plate into or withdraw it from the cutters or shears, and it has relation particularly to the special form of the same wherein the to-and-fro movable disk is secured to the actuating pressure-screw by a ball-and-socket coupling for the purpose of admitting of said disk adjusting itself to the inequalities or unevenness in the plane of the plate or sheet of metal between the disks, and thereby cause both disks to bite or contact with the plate throughout the entire area of their biting or contact surfaces to firmly hold the plate without imposing torsional strain on the pressure-screw. In said devices as heretofore constructed, so far as I am aware, the actuating pressure-screw is rotated to advance the movable head or disk to and withdraw it from the other disk, and also to impose the necessary clamping-pressure on the disks. In practice it has been found that when said clamping-pressure is large, as is the case for thick heavy plates, and the disks and plate clamped between them are rotated on their axis to feed the outer rim or edge of the plate to and withdraw it from the shears, the pressure-screw also partakes of such rotary movement, and if such movement be in the direction of the pitch of the threads on

the screw the latter is turned to impose additional clamping-pressure on the disks to prevent or interfere with the freedom of said rotary movement of the disks and plate, and if such rotation is in a direction opposite that of the pitch of said threads it reversely turns the screw and diminishes the clamping-pressure on the disks.

My invention has for its objects to avoid said described objections; or, in other words, to so construct or arrange the pressure-screw that it does not rotate to clamp the disks to the plate inserted between them, and admits of a rotary movement of the disks and plate without affecting the screw or its pressure upon the disks; to provide a positive instead of a frictional bite for the rocking disk; to means for initially adjusting the holding device longitudinally to and from the cutters to suit or accommodate different sizes of plates to be trimmed; to other and separate means for finally or terminally adjusting the holding device longitudinally to admit of the successive withdrawal of a trimmed plate and the insertion of a plate to be trimmed when it is desired to operate upon a number of plates of the same size; to means for securely fastening the holding device in position when terminally adjusted, and to means for limiting the oscillating movement of the holding device at a position the most suitable for presenting the plate to the cutters.

My invention accordingly consists of the combinations, constructions, and arrangements of parts, as hereinafter described in the specification and more particularly pointed out in the claims.

Reference being had to the accompanying drawings, Figure 1 is an elevation, partly in section, of a screw-clamp holding device for sheet-metal plates having actuating pressure-screw, terminal longitudinal-adjustment mechanism, means for limiting its oscillating movement, and showing it arranged to be initially moved longitudinally to and from the shears by weight or manual pressure exerted against it. Fig. 2 is a side elevation of the same, drawn to a small scale, and showing mechanism for initially moving the device

longitudinally, stop-bar for limiting the oscillating movement of the device, and terminal longitudinal-adjustment mechanism. Fig. 3 is a plan of the bed-plate for the holding device, the latter being removed. Figs. 4 and 5 show, respectively, an inverted plan and a sectional elevation of a form of clamping-disk having set-screws with knife-edges for a positive bite or contact with the sheet or plate of metal. Figs. 6 and 7 are respectively an inverted plan and an elevation of a modified form of same. Figs. 8 and 9 are corresponding views of still another modification of same. Fig. 10 is a plan of detail part for the actuating pressure-screw. Fig. 11 is an elevation, partly broken away, showing modification of devices for longitudinally moving the holding device. Fig. 12 is a sectional elevation, drawn to an enlarged scale, of part of the holding device, part of the bed-plate therefor, axial or pivotal connection between said parts, and terminal longitudinal-adjustment and locking mechanism for the holding device. Fig. 13 is a plan of holding device, showing more plainly the position of its stop-bar and its axial or pivotal connection with bed-plate; and Fig. 14 is a plan of such axial or pivotal connection and terminal longitudinal-adjustment mechanism for holding device.

A represents the holding device, consisting, essentially, of a yoke-shaped frame or housing *a*, in the lower limb *a'* of which is suitably supported, so as to rotate on its axis, 35 a clamping head or disk *B*, which, as shown, is mounted upon a short spindle *b*, having its bearing in a socket *a²* in limb *a'*, and between the end of spindle *b* and the bottom of socket *a²* are inserted one or more steel or 40 other suitable washers *b'*, to prevent wear on the bottom of socket *a²*, and by means of which the height of the disk *B* above the limb *a'* may be adjusted as desired. The limb *a³* of yoke *a* at its outer end is provided 45 with a tubular bushing *C*, threaded in its bore *c* for engagement with a screw *D*. Said bushing may be constructed and secured in position in any suitable manner, and has at its upper end a hand-wheel *E*, through the 50 smooth bore of which the screw *D* passes, as shown more plainly in Fig. 1. The screw *D* is provided with one, two, or more longitudinal slots *d*, which engage with feathers or studs *f* in an opening *f'* in a plate *F*, firmly secured, 55 as indicated at *f''*, to the limb *a³*, to prevent the screw *D* from rotating. At the lower end of screw *D* is secured a clamping head or disk *G* in any suitable manner; but I prefer to use a ball-and-socket-coupling connection *g* 60 for the same, so that the disk *G*, when contacting with a plate or sheet of metal on disk *B*, will have a rocking motion to adjust itself to the plane of the plate or sheet of metal and cause both disks to bite the metal throughout 65 the entire area of their biting-surfaces and without imposing any torsional strain on screw *D*, as fully explained in United States

Letters Patent dated November 22, 1887, No. 373,672. By turning the hand-wheel *E* the bushing *C*, connected therewith, is rotated to move the screw *D* up and down to advance the disk *G* to or withdraw it from the disk *B*.

As the screw *D* does not rotate to effect the described movement of the disk *G*, the disks *G* and *B*, together with the plate inserted between them, when under clamping-pressure, can be readily rotated to feed the outer rim or edge of the plate to the shears or withdraw the same therefrom independently of the screw or without affecting or varying the clamping-pressure on the disks. The plate therefore is firmly held in position between the disks, and the latter, with the plate, can be freely rotated on their axis in any direction when under pressure of screw *D*.

As plate *F* is removable from limb *a³* and the disk *G* is detachable from screw *D* and the hand-wheel from sleeve or bushing *C*, all of said parts are susceptible of being easily removed from the holding device *A* for repairs or replacement.

The holding device *A* is pivoted or axially connected to a bed-plate *H* by a bolt *h*, and I prefer to provide for such connection as shown in Fig. 12, wherein the bed-plate *H* is provided with a longitudinal inverted-T-shaped slot *h'*, in which is located the head *h²* of the bolt *h*. The latter passes through a sleeve *h³*, having at its bottom a reduced part or shoulder *h⁴*, which snugly fits in the narrow limb or part of the bed-plate slot *h'* to prevent lateral movement of said bolt, sleeve, and consequently of the holding device *A*. Above said sleeve-shoulder *h⁴*, and resting on the top of the bed-plate, is an enlarged collar or flange *h⁵*, which, together with the sleeve *h³*, fits in a corresponding opening or bearing *h⁶* in another sleeve *h⁷*, which bearing *h⁶* is eccentric with the periphery of sleeve *h⁷* to make it an eccentric sleeve, and it fits or has its bearing in a hub *h⁸* on the holding device *A*. The top of sleeves *h³* and *h⁷* are practically flush with the top of the hub *h⁸*, and upon which is placed a washer *h⁹*, against which impinges a nut *h¹⁰* upon the upper threaded end of bolt *h* for securing said parts together. The eccentric sleeve *h⁷* is provided with a laterally-projecting handle or lever *h¹¹*, which projects through a segmental slot *h¹²* in hub *h⁸*. (See more plainly Fig. 14.) The lever *h¹¹*, if desired, is provided with any suitable spring-pawl attachment *h¹³* for engaging with recesses *h¹⁴* in the adjacent surface of the slot *h¹²* in hub *h⁸* to hold the eccentric sleeve in its adjusted position.

The bolt *h* and sleeve *h³* form the pivotal connection for the holding device *A* to admit of oscillating the same on such pivotal connection. The eccentric sleeve *h⁷* forms the mechanism for terminally adjusting the device longitudinally, and the nut *h¹⁰* on bolt *h*, in conjunction with the washer *h⁹*, forms the means for locking said parts in their adjusted positions to correspondingly secure the hold-

ing device A in its adjusted position, as hereinafter described.

In Fig. 1 the holding device A is shown without mechanism separate from the eccentric sleeve h^7 for moving it longitudinally. Hence, to impart to it the initial longitudinal movement to and from the cutters, in order to admit of oscillating the holding device A, the nut on bolt h is loosened, and manual or other pressure is applied to the holding device. I prefer, however, to secure the holding device A to a separate bottom piece I, Figs. 2 and 3, by means of said described pivotal connection, and at the forward end of the bottom piece I mount thereon in suitable bearings or brackets i a transverse shaft i^5 , having a gear-wheel i^2 , which meshes with a rack h^{31} , secured to or formed on the bed-plate H. At opposite ends of shaft i^5 are ratchet-wheel and hand-pawl mechanism K K', respectively, which may be arranged to work or be worked right and left, as shown more plainly in Fig. 3, so that by operating the pawl-levers k' in the proper direction the shaft i^5 and gear-wheel i^2 are rotated to effect a to-and-fro sliding movement of the bottom piece I and device A on the bed-plate H. To bed-plate H or to bottom piece I, at any suitable place thereon, as shown more plainly in Fig. 13, is secured a bracket or standard L, having in its top a set-screw l , for the purpose of limiting or stopping the movement of the device A on its pivot-bolt h . Instead of securing the rack h^{31} to bed-plate H, the same may be secured to the housing or frame of the cutter or shearing-machine, as indicated in Fig. 11, and, if desired, the ratchet-wheel and hand-pawl mechanism on shaft i^5 may be dispensed with, in which case the ends of shaft i^5 may be made angular, as shown in Fig. 11, for the reception of hand cranks or winches for actuating shaft i^5 and gear-wheel i^2 .

The biting-surfaces of the disks B and G may be smooth, as indicated in Figs. 1 and 2, to frictionally hold the plate between them, or they may be covered or provided with leather, rubber, or other suitable elastic material l' (see Figs. 8 and 9) to increase the bite of the same. For thick heavy plates I prefer to provide the disks with slightly-projecting knife-edges, either in the form of tubular set-screws m , with lower knife-edges m' suitably disposed around the disks, or in the form of radially-arranged bars n , with knife-edges, as shown in Figs. 4 and 5 and in Figs 6 and 7, respectively.

The advantage of using the tubular screws m is that they can be adjusted, as desired, to more or less project their knife-edges beyond the surface of the disks to increase or diminish their bite, as the requirements of the work demand.

The operation is as follows: The nut h^{10} on bolt h is first loosened, and the device A is initially longitudinally moved toward the cutters by means of the levers k' , or, when these are not used, by applying pressure di-

rectly to the device A. The latter is then swung on its pivotal connections away from the stop-bar, and a size of plate is inserted 70 between the disks B G, and the actuating screw-pressure is applied thereto. The device A is then swung on its pivotal connections in a reverse direction until it meets the set-screw l on stop-bar L, which set-screw is 75 adjusted to stop the device A at a proper or suitable location to bring the outer rim of the plate in line with the cutters. By suitably manipulating the eccentric sleeve h^7 the holding device is then terminally moved longitudinally to bring the plate to the cutters to be trimmed, and when such adjustment is made the pawl h^{12} on eccentric-sleeve handle h^{11} , engages with one of the recesses h^{14} in segmental slot h^{13} to hold the eccentric sleeve h^7 in 80 position, and the nut h^{10} is screwed down on washer h^9 to firmly clamp the holding device A in position. The disks B and G, with the plate between them, are then rotated on their axis to feed the outer rim or edge to the cutters 85 to be trimmed. By reversing said described movements the trimmed plate is withdrawn and another of different size inserted between the clamps. When successive plates of the same size are to be cut or trimmed, it is only 90 necessary to move the holding device longitudinally by means of the eccentric-sleeve h^7 , and the use of the latter also admits of making one or more rough cuts from the plate before the final cut is made to avoid bending 95 or drawing of the plate as a heavy cut is made.

It is obvious that the construction of the novel details above described may be variously made without departing from the spirit of my invention, and hence I do not limit myself to the same as shown and described.

What I claim is—

1. The combination, with a pivotally-supported holding device A, of a stop-bar L, having an adjusting-screw l , substantially as set forth.

2. The combination, with a pivotally-supported holding device A, of a stop-bar L and eccentric sleeve h^7 , substantially as set forth.

3. The combination, with holding device A and its bed-plate, of a pivotal connection between said parts and an eccentric sleeve with operating-handle within said pivotal connection, substantially as set forth.

4. The combination, with a holding device A, having a swinging-motion on a pivotal support, of mechanism for initially moving the device A longitudinally and separate mechanism for terminally adjusting the device A longitudinally, substantially as set forth.

5. The combination, with a holding device A, having sleeve-bearing h^8 , of a bed-plate, bolt-connection h , sleeve h^3 , and eccentric sleeve h^7 , having handle h^{11} and locking mechanism, substantially as set forth.

6. The combination of a holding device A, having a swinging motion on a pivotal support, stop-bar therefor, mechanism for ini-

tially longitudinally moving said device, and separate mechanism for completing such longitudinal movement, substantially as set forth.

7. The combination of a yoke-frame A, the head or disk B, vertically-sliding screw D, rotating tubular sleeve or bushing C, engaging with said screw and having hand-wheel E, and disk or head G at the lower end of screw D, substantially as set forth.

10. 8. The combination of yoke-frame a, tubular sleeve or bushing C, threaded in its bore and having hand-wheel E, the vertically-sliding screw D, engaging with sleeve C, head or disk G, and ball-and-socket connection between disk G and screw D, substantially as set forth.

9. The combination of yoke-frame a, rotating disk B, tubular sleeve C, threaded in its bore and having hand-wheel E, screw D, engaging with sleeve C and having longitudinal slots d, plate F, having studs f, engaging with screw-slots d, and head or disk G at the lower end of screw D, substantially as set forth.

10. 10. In a holding device A, the disk G, having supplementary biting-surfaces, substantially as set forth.

11. In a sheet-metal holding device A, the rocking clamping disk or head G, provided with supplementary biting-surfaces, substantially as set forth.

12. In a sheet-metal holding device A, clamping disks or heads, supplementary biting surface or surfaces on said disks, and actuating pressure-screw, substantially as set forth.

13. In combination with the rotatable sheet-metal holding device A, the stop-bar L, substantially as set forth.

14. In combination with the rotatable sheet-metal holding device, a bed-plate and mechanism interposed between the bed-plate and holding device for sliding the latter upon the former, substantially as set forth.

15. In combination with the sheet-metal holding device A, the bottom piece I, bed-plate H, and mechanism interposed between bottom piece I and bed-plate H for sliding the bottom piece on the bed-plate, substantially as set forth.

16. The combination of sheet-metal holding device A, bottom piece I, pivotal connection between holding device A and bottom piece I, shaft i⁵, having gear-wheel i², mounted on bottom piece I, and bed-plate H, having rack h³, engaging with wheel i², substantially as set forth.

17. The combination of bed-plate H, bottom piece I, holding device pivoted to bottom piece I, stop-bar L on the latter, and mechanism interposed between the bed-plate H and bottom piece I for sliding the latter on the former, substantially as set forth.

In testimony whereof I affix my signature in presence of two witnesses.
